CHECK CONTROLLED STOP DEVICE

Harvey E. Marvel, Fort Wayne, Ind., assignor to
 S. F. Bowser & Company, Incorporated, Fort
 Wayne, Ind., a corporation of Indiana

Application December 23, 1942, Serial No. 469,963

6 Claims. (Cl. 194—66)

This invention relates to a mechanism for a liquid dispensing apparatus which is preset, by means of a check, to deliver a predetermined amount of liquid and to thereafter prevent delivery of additional liquid until after an additional check or checks have been deposited.

More specifically, it relates to a stop mechanism which is preset, upon the insertion of a check or checks, to deliver a predetermined quantity of liquid and to thereafter close a valve in the dispensing line and prevent the opening of the valve until an additional check or checks are inserted in the machine.

An object of the invention is to provide means for setting a control device manually to permit dispensing and for locking it in dispensing position.

Yet another object of the invention is to provide means for automatically returning a control device to dispensing preventing position and for preventing its movement from such position until a required conditioning operation is performed.

Still another object of the invention is to provide means for releasing the control device for manual setting to dispensing position when a credit is posted on the predetermining mechanism.

These and other objects will be apparent from a study of this specification in connection with the drawings which are attached hereto and made a part hereof, and in which:

Figure 1 is an elevation with parts broken away of a dispensing apparatus showing the control mechanism connected to it.

Figure 2 is a view of the trip mechanism and valve control mechanism in the actuated or flow preventing position.

Figure 3 is an expanded view of the trip mechanism and its drive gearing.

Figure 4 is an elevation showing the valve control and the check handling mechanisms.

Figure 5 is a sectional view of the valve and valve control mechanism.

Figure 6 is a sectional view taken on line 6—6 of Figure 5 showing the valve and valve operator.

Referring now to Figure 1, numeral 11 represents a suction pipe which is connected at one end to a source of liquid, such as gasoline in a storage tank, and to a pump 15 at the other end. A motor 17 drives the pump and the liquid discharged therefrom passes through an air separator 19, through pipe 1 to a meter 21 and thence through suitable piping and a hose to a dispensing nozzle 27.

A switch 29 controls the motor 17 and is operated by a rod 31 which is connected to a nozzle support 33. The support is controlled by a reset interlock mechanism 41 which prevents it from being moved up to the motor on position until the registering mechanism indicated generally by

73 has been reset to zero. This is accomplished by the shaft 47 and crank 39.

The meter drives a shaft 69 through suitable gearing 71 and the shaft drives a gear reduction mechanism 75. This mechanism drives a flexible shaft 101 housed in the tube 77, and drives the pinion 123 (Fig. 3) of the check operated predetermining mechanism indicated generally by numeral 79 in Figure 1.

10 Pinion 123 drives lever 201 through gears 133, 141, 145, 147, a sector gear 171, a multilated pinion 177, gears 187 and 191, the latter of which carries the lever. As is shown in Figure 2, lever 201 carries a pawl lever 205 which is provided for with a tooth 207 and an extension 209 which has a nose 211. A spring 217 connects a pin 213 on 15 209 with a pin 215 on gear 191. The tooth 207 rides upon the periphery of a disk 373 which is provided with a notch 379, while the nose 211 is adapted, when it is drawn down by the spring 217, to engage a tooth 327 on starwheel 381. The starwheel is mounted for free rotation on the hub of the disk 373 and has connected to it a link 323 which is pivoted at 295 to one arm of a lever 297 which is, in turn, pivotally mounted on a pin 203. A spring 301 (Fig. 2) normally urges 20 the lever in a clockwise direction. The starwheel is actuated by pawl 211 when the tooth 207 rides into the notch 379 of disk 373. The arm 201 moves in a clockwise direction (Fig. 2) when it is driven by the meter and is never moved in the opposite direction.

The disk 373 is rotated counter-clockwise (Fig. 2) nine-tenths of a revolution for each token inserted in the machine to position the notch 379 one-tenth of a revolution ahead of the tooth 207 for each token.

35 The knob 233 (Figs. 3 and 4) drives a hub 235 upon which are fixedly mounted a full stroke disk 247 which has plates 241 mounted thereon to form token receiving pockets 243 and 245. The disk has two sets of ratchet teeth 237 on its periphery which are adapted to be engaged by a yieldable, non-return pawl 255.

40 A pawl 275 is mounted to enter the check pockets and prevents rotation of the ratchet 247 to the place where it would be engaged by pawl 255 so long as no check is in the uppermost pocket. This pawl is cammed out of the way 45 by a check in the pocket, and the other pocket is then caught by the pawl to limit the rotation of the handle.

A gear sector plate 329, having groups of teeth 333 and 335 on its periphery, is mounted to rotate 50 with the knob. The teeth mesh with a gear 345 which drives a gear train 367, 369 and the disk 373 described above. A locking sector disk 381 carrying sectors 353 and 357 serves to lock the sector 363 and, consequently, the gear train 55 60 against rotation when the gear sectors are out of mesh with gear 345.

A cam 289 is also mounted to rotate with the knob and operates a cam follower lever 281. This lever is pivoted on pin 161 and engages pin 295 on the lever 297 as the knob is rotated so as to move lever 297 in a counter-clockwise direction for the period required to post a credit on disk 373.

A fixed pin 253 mounted on the casing 167 serves to cam checks out of the check pockets as the credit represented by them is set up, and these checks fall into a chute 425 and check tube 407.

A check slide 411, having an opening 413 big enough to receive a check, is actuated by a link 419 and a crank 229 which is operated by the 15 meter driven gear 123 through gears 133, 141, 145, 147, 151, 153 and 219.

Near the end of the advance of the cam follower lever 205, each one-tenth revolution, the crank 229 completes a revolution and discharges a check from the check tube 407 to the check safe or drawer 403 through an opening 401 in the slide support.

The mechanism thus far described is disclosed in the patent to R. H. Damon et al., Number 2,247,480, issued July 1, 1941.

Referring now to Figure 1, a valve 501 is connected in the pipes 1 and serves to permit flow from the pipe 11 to the nozzle 27 when it is open and to stop the flow when it is closed. The valve is operated by a rotary stem 503 (Figs. 2, 5 and 6) which is housed in a sheath pipe 505 which passes through the back plate 504 of the mechanism 79.

A valve port 507 (Figs. 5 and 6) is closed by a poppet type valve 509 which is held on its seat by a spring 513. A collar 519 is fixed on the stem 515 of the valve and a bifurcated shifter 517 mounted on shaft 503 coacts with the collar 519 to open the valve against the spring 513 which normally holds the valve closed.

In Figure 5, numeral 521 represents a bracket which is fixed to the back plate 504 and which is perforated to serve as a bearing for the hollow shaft 513. This shaft is supported by the end of shaft 503 and carries on one end an actuating lever 524 and on the other end an upstanding arm 525 upon which is pivotally mounted the pawl 527 which is urged in a counterclockwise direction (Fig. 4) by spring 529. A spring 531 is supported on shaft 523 and bears on arm 525 and on the bracket 521 to urge the arm 525 and lever 524 in a clockwise direction (Fig. 2).

In Figure 5, 533 is a hub which is fixed on shaft 503 and which has fixed on it a ratchet 535 having two teeth or notches 537 and 539. The pawl 527 is adapted to engage notch 537 while a holding pawl 541 which rotates on a pivot pin 543, supported by bracket 521, is adapted to engage notch 539. A spring 545 urges the pawl into engagement with the ratchet 535. The pawl 527 and ratchet 535 constitute a clutch for transmitting motion from lever 524 to shaft 503.

A pawl knockout device comprises a bifurcated element 547 which straddles the hub 533, riding in a groove formed by a recess 549 and the ratchet 535. The element has a peripheral cam 551 which is adapted to engage both pawls 527 and 541 when the element is drawn to the left in Figures 2 and 4 and to disengage the pawls from the ratchet. The element is attached to a link 552 which is pivotally connected to the upper end of lever 297.

The lever 524 operates in a slot 553 which is formed in the front plate of the mechanism 97.

Two stops 555 and 557 are also set in the bracket 521 and engage the arm 525 to limit its movement.

Operation

Assuming that there is no credit established on the predeterminer and that the valve is closed, the operator will place a check in the uppermost check pocket. Upon rotation of knob 233, the latch 215 will be cammed out and the non-return pawl 255 will engage the teeth 237 to compel the operator to complete the stroke. As the knob rotates, the gear teeth 333 or 335 of sector gear 329, whichever ones are in operating relation with pinion 345, will operate the trip cam 373 nine-tenths of a revolution to position notch 375 one-tenth of a revolution ahead of the trip pawl 205. This action will be repeated for every token put in and the credit will be represented by the distance separating the pawl and notch. The checks deposited are accumulated in the tube 407.

The cam 289 and follower 281 insure that the valve is closed during the deposit of a check.

When the lever 205 is lifted by the camming of pawl 207 out of notch 379, the lever 211 is lifted against spring 217 to permit starwheel 381 and lever 297 to be rotated by spring 301. The motion of 297 being clockwise, Figures 2 and 4, the link 552 will be pushed to the right and the periphery 551 of the knockout element will be moved to the right, to the Figure 2 position, to permit the pawls 527 and 541 to ride on the periphery of the ratchet 535.

By moving lever 524 to the right (Fig. 4) the hollow shaft 523, arm 525 and pawl 527 will be rotated counter-clockwise (Figs. 2 and 4) away from stop 555 and pawl 527 will engage notch 537 in the ratchet. When this occurs, shaft 503 will be picked up and, upon further rotation, the valve will be opened against the action of spring 513. Pawl 541 will engage notch 539 in the ratchet and hold it against return by valve spring 513. The stop 557 limits the movement of the lever 524 and arm 525 and as soon as pressure is released on the lever, the spring 531 returns it, arm 525 and pawl 527 to the Figure 4 position with arm 525 against stop 555.

As soon as a check has been deposited in the tube 407 and the valve has been opened, the operator may reset the register 73, remove the nozzle from the hose hook and lift the hose hook 33 to start the motor 17 and pump 15, whereupon liquid will be delivered under pressure to the nozzle and it may be dispensed under control of the usual nozzle valve. As dispensing occurs, the meter 21 drives the register 73 and the trip arm 210 by means of the shaft 101 and the gear train described above, to advance the pawl 207 toward notch 379 in the cam 373. Near the end of each one-tenth revolution of the arm 210, the crank 229 will position the opening 413 in slide 411 over the opening 401 and a check will drop into the safe 403.

As the last deposited check is expended, the trip pawl 207 rides into the notch 379, the spring 217 causes the nose 211 of lever 209 to be pulled down upon a tooth 327 of the starwheel and overcomes springs 301, 545 and 529 so that the lever 297 will be rotated counter-clockwise (Figs. 2 and 4) and will draw link 552, cam 551 and pawls 527 and 541 to the left. As soon as the pawl 541 is withdrawn from the notch 539, the ratchet 535, shaft 503 and the valve will be moved by the valve spring 513 to the valve closing position.

Since the pawl 527 is held away from the periphery of the ratchet, operation of lever 524 will have no effect until another token is deposited and the pawls 207 and 211 are withdrawn from the trip notch 379 and the starwheel respectively. When this occurs, the spring 301 will rotate lever 297 and its associated parts to the Figure 4 position so that actuation of the lever 524 will open the valve.

The lever 281 is actuated each time the knob 233 is rotated to place a credit on the machine, and serves to rotate lever 297 and actuate the associated parts to cause the valve to close. Consequently, the valve must be reopened after the insertion of every check. This mechanism serves to prevent an operator from dispensing liquid with disk 373 in an intermediate position and to thus prevent the delivery of more than the amount of liquid represented by the check.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What I claim to be new and desire to protect by Letters Patent of the United States is:

1. In a stop mechanism, the combination of a check presettable predetermining mechanism having preset and stop positions, means for receiving checks and variably presetting said mechanism in proportion to the value of the checks received, a control device having starting and stopping positions, manual means for moving said control device to starting position, including a manually operable element and disengageable means for connecting said element to actuate said control device, means operable by said mechanism when it occupies its stop position for actuating said disengageable means to disconnect said element and said control device, and releasable means for holding said control device in starting position, said operable means also being adapted to release said holding means when credit is exhausted.

2. In a stop mechanism, the combination of a check presettable predetermining mechanism having preset and stop positions, means for receiving checks and variably presetting said mechanism in proportion to the value of the checks inserted therein, means for actuating said mechanism to its stop position, a control device having starting and stopping positions, manual means for moving said control device to starting position comprising an actuator, a ratchet connected with said device, a pawl connected with said actuator and adapted to releasably engage said ratchet, a pawl adapted to engage said ratchet to hold said device in starting position, yieldable means for normally holding said pawls against the ratchet, and a cam connected for operation by said mechanism and adapted to cam said pawls from said ratchet when said mechanism occupies its stop position.

3. In a stop mechanism, the combination of a check presettable predetermining mechanism having preset and stop positions, comprising an element movable between running and stop positions, means for receiving checks and variably presetting said mechanism in proportion to the checks received and for moving said element to running position, means for moving said element to stop position when said mechanism occupies its

stop position, a stop device having stopping and starting positions, a manually operable member, means including an automatically engageable clutch for transmitting motion from said manually operable member to said stop device and adapted to move the latter to starting position, yieldable means for normally holding said pawls against the ratchet, means for releasably holding said device in starting position, means operable by said element as it is moved to stop position for releasing said holding means and for disengaging said clutch, and means for moving said stop device to stopping position.

4. In a stop mechanism, the combination of a check presettable predetermining mechanism having preset and stop positions, means for receiving checks and variably presetting said mechanism in proportion to the value of the checks inserted therein, means for actuating said mechanism to its stop position, a control device having starting and stopping positions, manual means for moving said control device to starting position comprising an actuator, a ratchet connected with said device, a pawl connected with said actuator and adapted to releasably engage said ratchet, a pawl adapted to engage said ratchet to hold said device in starting position, yieldable means for normally holding said pawls against the ratchet, a cam connected for operation by said mechanism and adapted to cam said pawls from said ratchet when said mechanism occupies its stop position, and means for returning said control device to stopping position.

5. In a stop mechanism, the combination of a check presettable predetermining mechanism having preset and stop positions, means for receiving checks and variably presetting said mechanism in proportion to the value of the checks received, means for actuating said mechanism to its stop position, a control device having starting and stopping positions, manual means for moving said control device to starting position comprising an actuator, a ratchet connected with said device, a pawl connected with said actuator and adapted to releasably engage said ratchet, stop means for limiting the movement of said actuator, a pawl adapted to engage said ratchet to hold said device in starting position, means for yieldably holding said pawls against said ratchet, and a cam connected for operation by said mechanism and adapted to cam said pawls from said ratchet when said mechanism occupies its stop position.

6. In a stop mechanism, the combination of a check presettable predetermining mechanism having preset and stop positions, means for receiving checks and variably presetting said mechanism in proportion to the value of the checks received, means for actuating said mechanism to its stop position, a control device having starting and stopping positions, manual means for moving said control device to starting position comprising an actuator, a ratchet connected with said device, a pawl connected with said actuator and adapted to releasably engage said ratchet, stop means for limiting the movement of said actuator, yieldable means for holding said actuator in position against said stop means, a pawl adapted to engage said ratchet to hold said device in starting position, yieldable means for holding said pawls against said ratchet, and a cam connected for operation by said mechanism and adapted to cam said pawls from said ratchet when said mechanism occupies its stop position.
